UNITED STATES PATENT OFFICE.

WILLIAM E. BARROWS, OF HARTFORD, CONNECTICUT.

COVER AND COOLER FOR BUTTER AND OTHER ARTICLES.

SPECIFICATION forming part of Letters Patent No. 224,126, dated February 3, 1880.

Application filed August 15, 1879.

To all whom it may concern:

Be it known that I, WILLIAM E. BARROWS, of Hartford, in the county of Hartford and State of Connecticut, have invented a new and 5 useful Improved Cover and Cooler for Butter and other Articles, which improvement is fully set forth in the following specification, reference being had to the accompanying drawings.

10 My invention relates to a device especially adapted for use on the table, the purpose of the same being to keep butter or other articles cool by ice without the ice coming into immediate contact with the butter or other article.

15 My invention consists, first, in a cover for a dish or plate, or for butter or other article thereon, having a receptacle or chamber for ice, which ice-chamber is above the article covered, and has a removable lid; secondly, 20 in such cover and ice-chamber so combined with a hollow base as by circulation of cold air to secure further cooling-surface.

In the drawings, Figure 1 is a perspective view of a cover and cooler embodying my invention. Fig. 2 is a vertical central section of same. Fig. 3 is a vertical central section taken at right angles to section shown in Fig. 2.

25 A is the main body of the cover and cooler. 30 B is a receptacle, dish, or chamber for holding the ice, and has a removable lid, C. In this form of construction of my cover and cooler the main portion A has an opening at its side, which may be closed by the slide D.

35 The opening in portion A is shown partially closed by the slide D in Fig. 1. The slide D is made like a cylinder, having a portion cut out corresponding to the opening in the portion A, likewise cylindrical, and is fitted to 40 revolve or slide about the portion A, having a knob, a, for convenience in moving the same.

The above-described parts are set on a base, E, which is hollow. A tube or passage, F, opens at the upper end, b, into the ice-chamber B, and at the lower end, c, into the hollow

base E. There are openings through the shell of the hollow base E at convenient place or places, as at f.

The operation of my device, constructed as above described, is as follows: Butter or other 50 article having been placed within the portion A and under cover of the portion A and chamber B, the slide D closed over the opening in the portion A, and ice placed in the chamber B, the whole will be cooled by the proximity 55 of the ice, and the butter or other article will be kept cool as long as ice remains in the chamber B; also, a circulation of cold air will be maintained by air passing from outside into the chamber B, there being more or less 60 opening about and under the rim of the lid C, and down the tube F into the hollow base E, and out through the openings f.

If the base E be removed, as it may be by loosening the fastenings g g, and the opening in the side of portion A closed, and in this form the cover and cooler be placed over butter or other article put on a suitable dish or plate, the purpose of my invention will be mainly served.

70 The cover and cooler may be made wholly of metal or other material—as, for instance, glass. So, also, the cylindrical part A may be made in various designs—that is, need not be confined to the straight form shown.

75 I claim as my invention—

1. The combination of the inclosing portion A, slide D, and ice-chamber B, substantially as hereinbefore described.
2. The combination of the inclosing portion 80 A, ice-chamber B, slide D, and hollow base E, substantially as hereinbefore described.
3. The combination of the inclosing portion A, having the slide D, ice-chamber B, base E, and tube or passage F, substantially as and 85 for the purpose hereinbefore set forth.

WILLIAM ELIOT BARROWS.

Witnesses:

JOHN SCOTT,
C. H. ROBBINS.
